APPARATUS FOR CONTROLLING SHEET THICKNESS IN CONTINUOUS STRIP MILLS

Alexander Shayne and Alexander Zeitlin, New York, N. Y., assignors, by mesne assignments, to Sperry Products, Inc., a corporation of New York

Application March 20, 1941, Serial No. 384,268

7 Claims. (Cl. 80—35)

This invention relates to the continuous rolling of hot strips in a continuous rolling mill. In these mills a short thick slab of metal which is discharged from the furnace at high temperature is passed successively through a series of rolling mill stands, usually 10 in number, each of which applies pressure to cause repeated thinning out of the material until finally it issues from the No. 10 mill stand as a thin sheet of material several hundred feet in length. It will readily be understood that one of the major objectives in this method of production of sheet material is to obtain as nearly uniform a product, so far as dimensions and crystalline structure are concerned, as possible. Thus it is extremely desirable to obtain a sheet of uniform thickness from one end to the other. This, however, has been found to be extremely difficult. There are various reasons why the thickness of a sheet varies, but chief among these is the taper which results from the fact that the forward end of the strip enters each mill stand sooner than the rear end and therefore the forward end is of a higher temperature. Since the amount of deformation is directly proportional to the temperature, it follows that with given pressure exerted between the rolls of any given mill stand, the forward end will be thinned out to a greater degree than the rear end which is cooler. Thus a taper results which in long strips may amount to as much as .020 inch.

It is therefore a principal object of this invention to provide a method and means whereby the thickness of the sheet passing through a continuous rolling mill may be maintained substantially constant from one end thereof to the other. This means will compensate not only for the tendency to taper but will compensate for other causes which may result in non-uniform thickness such as, for example, differences in chemical and crystalline structure in various portions of the sheet.

Further objects and advantages of this invention will become apparent in the following detailed description thereof.

The accompanying drawing is an assembly view, largely diagrammatic, disclosing one form of the invention.

Referring to the drawing, there are shown diagrammatically two mill stands which may be numbers 9 and 10 of a continuous rolling mill which would normally comprise ten such stands. Each stand includes side frame members 11 and a central cutout portion 12 in which are slidably mounted bearing blocks 13 and 14 which form the bearing members for large back-up rollers 17 and

18. Other bearing blocks 15 and 16, slidable in the first bearing blocks, form the bearing members for work rollers 19 and 20. Pressure is applied to the work rollers through the back-up rollers by means of a screw-down motor M which through suitable reduction gearing 21 operates screws 22 which apply pressure to the bearing blocks in which rollers 17 are journaled. In the set of ten such mill stands the first four stands 10 perform the roughing operation of bringing down the thickness of the slab into the form of a sheet. The mill stands 5-10 inclusive are the finishing stands which further reduce the sheet to a relatively thin, smooth strip. The slab of metal comes out of the furnace at high temperature and is slid on to conveyor rollers 31 which are motor driven, and these feed the slab into the mill stands. As the material passes through the pressure rollers it thins out and since it is constrained against any substantial increase in width the thinning causes a very substantial increase in length. The net result of this operation is that the forward end of the strip moves much more rapidly than the rear end, and progressively from 25 the forward end to the rear end the material has increasing time within which to radiate heat and become cooler. As explained in the introduction, this means that with any given pressure between the pressure rollers of the mill stand, the forward portion of the strip will tend to be deformed to a greater extent than the rear portion, so that there would be formed a taper from front to rear unless means were provided for overcoming this situation.

30 A solution for the problem thus presented is to utilize the pressure gauge which measures the pressure existing between the work rolls 19 and 20 of the mill stand as a means for setting into operation means for automatically regulating the pressure to increase or decrease the same as the case may be so as to maintain constant the thickness of the strip. Such a pressure gauge is disclosed, for example, in our copending application, Serial No. 384,212, for Strain gauge for rolling mills and the like, filed March 19, 1941. In said strain gauge a sensitive element 40, in the form of a wire fixed at one end to the upright frame portion 11 and movable at its other end, is caused to operate an indicator 41 in response to stretching of the frame due to pressure between the rolls. Since the pressure between the rolls is a function of the thickness of the strip passing therethrough, it will be understood that as the colder, less deformable portion of the strip passes 35 through the work rolls, said rolls will be spread

further apart and hence a greater pressure will be indicated by the indicator. This increase in pressure, over and above what the pressure should be for the required thickness, is caused to operate mechanism which will thin out the strip. If increased pressure were applied to the same mill stand which is indicating the thickness of the strip, it would only result in increased pressure indication in the indicator 41 which would mean that the strip passing therethrough is still thicker than it was before, where actually it is thinner. Therefore, if the sheet is to be thinned out, additional pressure must be applied in one of the preceding mill stands so that the sheet will come to mill stand 10 thinner and will therefore give an indication of lessened pressure, which is the operation desired. Thus, for example, the pressure indicator 41 is on No. 10 mill stand, and the desired pressure is set for a given thickness. Any increase in said pressure means that the strip passing through the work rolls is too thick. If, now, increased pressure is applied to the strip on one of the preceding mill stands such as No. 9 mill stand, then the sheet will be thinned out before entering No. 10 mill stand and the pressure indicator 41 will indicate lessened pressure. The pressure in No. 9 mill stand is increased until the pressure indicator at No. 10 mill stand is the desired pressure and therefore the desired thickness of material. However, the pressure may be increased on No. 10 stand if it is borne in mind that the excess over the desired pressure must be increased in order to thin out the material to the requisite degree.

In order to accomplish the above result, there is actuated from the pressure indicator 41 a potentiometer contact 50 operating over a resistance 51 so that, as the index 42 of the pressure indicator rises or falls, the pointer 50 will be rotated around its pivot 52 in one direction or the other. The potentiometer is arranged in parallel across the D. C. supply. A similar potentiometer is arranged in parallel across the same supply and includes a pointer 50' operating over a resistance 51' similar to resistance 51, the said pointer 50' being pivoted at 52' and settable by hand, as for instance by means of knob 53. In the well known manner, when the two potentiometers tap equal portions of the supply, the pointers 50, 50' do not tap an E. M. F.; but when pointer 50 moves above or below the point of equilibrium, due to the fact that the pressure between the work rolls 19 and 20 in mill stand 10 is increasing or decreasing due to thickness of the strip being greater or less than the thickness as determined by the setting of pointer 50', then an E. M. F. is tapped by pointers 50, 50' in one direction or the other, and said E. M. F. after being amplified by amplifier A may be caused to operate the screw-down motor M of mill stand 9 in such direction as to increase or decrease the pressure between the work rolls 19 and 20. This will thin out or thicken the material passing therethrough and thus will correct the pressure in pressure gauge 41 to a point where pointers 50 and 50' are again in equilibrium. For this purpose the output of amplifier A is caused to actuate a relay PR which may be of the polarized type, there being a polarizing coil 60 which normally holds an armature 61 in neutral position out of contact with contact 62 or 63 against the action of a spring 64. The output from amplifier A acts upon the coil 70 and, depending upon the direction of the signal, will cause armature 61 to engage contact 62 or contact 63 to close one or

the other of two circuits to motor M. One circuit lies through central contact 71 and a contact 72, while the other circuit lies through central contact 71 and a contact 73. Closing the circuit through contact 71 and 72 energizes motor M in a direction to raise the screw 22 and thus relieve the pressure between the work rolls 19 and 20 of the mill stand 9. Closing of the circuit through contacts 71 and 73 energizes the reverse winding of the motor M to operate screw 22 downwardly to increase the pressure between the work rolls and thus thin out the sheet. It will be understood that increase of pressure between the work rolls of mill stand 10 indicating excess thickness of material will operate pointer 50 in such direction as to close the circuit between contacts 71 and 73 to lower screw 22 and increase the pressure to thin out the material. The thinning out will continue until the pressure between the work rolls of mill stand 10 is sufficiently reduced to return arm 50 to balanced position where no E. M. F. is developed. Similarly, if the pressure between the work rolls of mill stand 10 decreases, it means the sheet is too thin and contact arm 50 will move in such direction as to close the circuit through contacts 71 and 72 to raise the screw 22 and thus allow thicker strips to pass out of mill stand 9 and into mill stand 10 to increase the pressure between the work rolls of mill stand 10 until such point is reached where arm 50 returns to balanced position.

If no material is passing through the mill stand, then there is a minimum of pressure between the work rolls of mill stand 10 and hence normally the circuit between contacts 71 and 72 would be closed to cause the motor M to operate screw 22 upwardly. This is undesirable because no material is passing through the mill stands and the thickness control mechanism should not work at this time. In order that the thickness control mechanism shall be rendered effective only when material is passing through the mill stands, there is provided a pivoted lever 80 which normally rests upon the conveyor rolls 31 and is held in contact therewith by spring 81. The other end of the lever 80 carries a contact 82 which when no material is passing through the mill stand 10 is out of contact with the cooperating contact member 83. The said contacts 82 and 83 are in the circuit of the coil 70, and therefore as long as no material is passing through the mill stands the control device is ineffective and the armature 61 is out of contact with contact 62 or 63. When material passes through the mill stand 10, it will lift the lower end of lever 80 to cause contacts 82 and 83 to close and thus render coil 70 and the control mechanism effective.

While the device is described as an automatic device for controlling thickness, there may be occasions when hand control will be desirable, and therefore there is provided means for quickly transferring control from the automatic thickness controlling device described above to hand control. For this purpose the contact 71 which is part of the two circuits through the motor M, one circuit including contacts 71 and 72 and the other circuit including the contacts 71 and 73, is itself in contact with the contact 85 at the lower end of a master control lever 86 pivoted at 87. As long as the control lever is in neutral position with contact 85 in engagement with contact 71, the automatic thickness control can operate through circuits lying through 71, 72 and 73. However, whenever no control is desired

the lever 86 is moved out of the central position so that contact 85 can engage contact 72 or contact 73. Such movement short-circuits the control relay and makes it possible for the motor M to be controlled directly from the master control handle 86.

While the pressure indicator has been described as located on mill stand No. 10 and controlling the thickness of the sheet by operating the screw-down motor on mill stand No. 9, it will be understood that the pressure indicator on any of the other mill stands may be utilized as the base, provided the screw-down motor on any of the preceding mill stands is controlled thereby.

In accordance with the provisions of the patent statutes, we have herein described the principle and operation of our invention, together with the apparatus which is now considered to represent the best embodiment thereof, but we desire to have it understood that the apparatus shown is only illustrative and that the invention can be carried out by other equivalent means. Also, while it is designed to use the various features and elements in the combination and relations described, some of these may be altered and others omitted without interfering with the more general results outlined, and the invention extends to such use.

Having described our invention, what we claim and desire to secure by Letters Patent is:

1. In a continuous rolling mill comprising a plurality of rolling mill stands, each stand comprising a plurality of rolls, the method of controlling the thickness of material passing through said stands which consists in measuring and indicating the pressure which exists between the rolls of the respective stands and causing variations from a predetermined indicated pressure in a selected stand to vary the pressure applied to the rolls of a preceding stand in such direction and to such degree that the indicated pressure in the first stand will return to the predetermined pressure.

2. In a continuous rolling mill comprising a plurality of rolling mill stands, each stand comprising a plurality of rolls, means for applying pressure to said rolls and means for indicating the pressure which exists between the rolls, means for controlling the thickness of material passing between said rolls, said last named means comprising means whereby variations of said pressure indicating means on a selected stand from a predetermined indication controls the pressure-applying means of a preceding stand in such direction and to such degree that the indicating means on the selected stand is returned to the predetermined indication.

3. In a continuous rolling mill comprising a plurality of rolling mill stands, each stand comprising a plurality of rolls, means for applying pressure to said rolls and means for indicating the pressure which exists between said rolls, means for controlling the thickness of material passing between said rolls, said last named means comprising means whereby variations of said pressure indicating means on a selected stand from a predetermined indication controls the pressure-applying means of a preceding stand in such direction and to such degree that the indicating means on the selected stand is returned to the predetermined indication, and means whereby said control means is rendered effective by the passage of material through the rolls of said selected stand.

4. In a continuous rolling mill comprising a

plurality of rolling mill stands, each stand comprising a plurality of rolls, a reversible screw-down motor for applying pressure to said rolls and means for indicating pressure which exists between the rolls, means for controlling the thickness of material passing between said rolls, said last named means comprising means whereby said indicator causes an electric current to flow in response to variations from a predetermined indicated pressure in a selected stand, and means whereby said current actuates the screw-down motor of a preceding stand in such direction and to such degree as to return the indicator of the selected stand to the predetermined indication.

5. In a continuous rolling mill comprising a plurality of rolling mill stands, each stand comprising a plurality of rolls, a reversible screw-down motor for applying pressure to said rolls and means for indicating pressure which exists between the rolls, means for controlling the thickness of material passing between said rolls, said last named means comprising a source of power, a pair of potentiometers arranged in parallel across said source, one of said potentiometers being settable by hand and the other of said potentiometers being operated from an indicator of a selected stand whereby an electric current will be caused to flow when said indicator indicates variations from a predetermined pressure as determined by the setting of said hand-set potentiometer, and means whereby said current actuates the screw-down motor of a preceding stand.

6. In a continuous rolling mill comprising a plurality of rolling mill stands, each stand comprising a plurality of rolls, a reversible screw-down motor for applying pressure to said rolls and means for indicating pressure which exists between the rolls, means for controlling the thickness of material passing between said rolls, said last named means comprising means whereby said indicator causes an electric current to flow in response to variations from a predetermined pressure in a selected stand, means whereby said current actuates the screw-down motor of a preceding stand in such direction and to such degree as to return the indicator of the selected stand to the predetermined indication, and means whereby the circuit traversed by said current is controlled by the passage of material through said selected stand.

7. In a continuous rolling mill comprising a plurality of rolling mill stands, each stand comprising a plurality of rolls, a reversible screw-down motor for applying pressure to said rolls and means for indicating pressure which exists between the rolls, means for controlling the thickness of material passing between said rolls, said last named means comprising a source of power, a pair of potentiometers arranged in parallel across said source, one of said potentiometers being settable by hand and the other of said potentiometers being operated from an indicator of a selected stand whereby an electric current will be caused to flow when said indicator indicates variations from the predetermined pressure as determined by the setting of said hand-set potentiometer, means whereby said current actuates the screw-down motor of a preceding stand, and means whereby the circuit traversed by said current is controlled by the passage of material through said selected stand.
